SEGMENTAL PUMP LEVER FOR USE WITH
DRIVING MEANS OF DIFFERENTLY CON-
STRUCTED ENGINES

Morris Katcher, New York, N. Y.

Application April 6, 1946, Serial No. 660,189

11 Claims. (Cl. 103—215)

1

This invention relates to pumps for use with internal combustion engines. The pumps may be for pumping fuel, or for pumping air to create a vacuum, or to create pressure greater than atmospheric, or the pumps may be combined fuel and air pumps. These various types of pumps are well known to the art.

It is an object of this invention to provide a segmental operating lever to enable standard pumps of these various kinds to fit and to be operated by many different types of motors. The use of the segmental lever, having a standard segment and a replaceable segment, makes possible the reduction to a small number of standard pumps, of the large number of special pumps which must be supplied at present for various motors. At present, in so far as the driving cam location is different for each type of motor, a special driving lever has been necessary in each case. In my pending applications, Serial Nos. 600,782, now Patent Number 2,440,175, 633,333 and 644,535, this is accomplished by having a standard pump with special levers pivoted in detachable brackets which fit the standard pump to each particular motor. The present invention simplifies this. The removable bracket is done away with. Instead, an operating lever is used which is split in two parts or segments. One part or segment is the same or standard for a given line of pumps and is pivoted in the pump body and assembled with it permanently. The special part or segment of the lever is made to fit the given driving arrangements of a particular motor, removably to engage the standard segment and to fit over the latter's pivot. The two segments interlock and are held together by means of a readily removable pin. The attachment of the segments is such as to produce a rigid operating lever.

Other objects and advantages will become apparent upon further study of the description and drawings, in which:

Fig. 1 is a vertical section through the pump.

Fig. 2 is a front elevation shown with the guides of the operating bar omitted.

Fig. 3 is a perspective view of the clip for receiving the pressure of the return stroke spring of the operating lever.

Fig. 4 is a partial section taken along the line 4—4 of Fig. 1.

Fig. 5 is a plan view of a modified form of operating lever shown attached to the diaphragm stem, most of the other parts of the pump being omitted. The removable segment and the standard segment both differ from those shown in Figs. 1 and 9.

Fig. 6 is an elevation of the lever of Fig. 5

2

shown attached to a fragment of the diaphragm stem.

Fig. 7 is a section taken along the line 7—7 of Fig. 6.

Fig. 8 is a plan, partially in section, taken along the line 8—8 of Fig. 9.

Fig. 9 is a partial vertical section through the pump showing another modified form of the detachable lever segment, the standard lever segment being the same as shown in Fig. 1.

Fig. 10 is a perspective view of the detachable lever segment of Fig. 9 shown by itself, and

Fig. 11 is a perspective view of one arm of the permanent or standard lever segment shown by itself.

Pump casing 16 is provided at its forward end with a mounting flange 17 which latter has bolt holes 18 through which bolts can be passed for mounting the pump on the engine casing, not shown. The upper part of casing 16 is formed with a flange 19. Flexible diaphragm 20 is set on top of flange 19 and is held there by bottom flange 21 of cover 22, both flanges being squeezed together with the diaphragm between them by bolts 23. A plate 24 is located on top of diaphragm 20 and a somewhat smaller plate 25 is mounted below the diaphragm. The reduced upper portion 26 of diaphragm stem 27 passes through plates 24 and 25, diaphragm 20 and

bolts 23. A plate 24 is located on top of diaphragm 20 and a somewhat smaller plate 25 is mounted below the diaphragm. The reduced upper portion 26 of diaphragm stem 27 passes through plates 24 and 25, diaphragm 20 and

washer 28, the whole assembly being gripped between rivet head 29 and shoulder 30. A ring 31 is loosely mounted on stem 27. Below ring 31 is a pin 34 set through stem 27. Pin 34 limits the downward movement of ring 31. With the

pump assembled, the downward limit of movement of ring 31 is controlled by the top of lever segment 33. Pin 34 only functions before stem 27 is set between arms 37 of lever segment 33.

Arms 37, Figs. 1, 4 and 11, constitute the standard part or segment of the operating lever. This segment can be made the same for all pumps irrespective of to what type of motor the pump is attached. A pivot pin 40 extends across casing 16 and through its side walls, see also Fig.

45. Sleeve 41 is set over pin 40, passing, where reduced in section, through holes 42, Fig. 11, in arms 37. Rivet 44 fastens arms 37 together in spaced relation at their rear portion. To enable the standard part to be driven by various types

50 of motor, a readily removable segment 35, Fig. 1, or segment 36, Figs. 8, 9 and 10 is attached to arms 37.

Segment 35 is provided with two upper prongs 38, Figs. 1 and 4, see also Fig. 10 and two lower and shorter prongs 39. Segments 35 and 36 are set over their respective pins 40 so that the latter come within the notch formed by prongs 38

and 39. Readily removable pin 13 passes through removable segments 35 and 36 and arms 37. Pin 13 is readily removed when spring clip 73, Fig. 8, is pulled out from under its head. Arms 37 are provided with punched out tongues or projections 43 against which prongs 38 bear when segment 35 is caused to rock or swing in a clockwise direction. A clip 14 has a hooked portion 45 which bears on sleeve 41. It also has two lugs 46 which enter corresponding openings 90 in arms 37, see Figs. 1, 3, 8 and 11. Tongue 47 on clip 14 receives the lower end of spring 48, the upper end of said spring reacting against the pump casing 16. Removable lever segment 35, Figs. 1 and 2, is provided with a cup 49 for receiving the upper end of actuating bar 12, the latter reciprocating in guide 50. The lower end of bar 12 rides on cam 51 fixed on motor shaft 52.

When bar 12 moves up, removable segment 35 interlocks with standard segment 33 turning it clockwise, prongs 38 bearing down on tongues 43, prongs 39 bearing up against and rotating about sleeve 41, and the main body of segment 35 pushing up on pin 13. Under pressure of spring 48 and as cam 51 rotates and lets bar 12 come down, removable segment 35 interlocks with standard segment 33, by means of pin 13 and sleeve 41, turning it counterclockwise, clip 14 bearing down on pin 13, its lugs 46 bearing down on arms 37 and tongue 45 bearing down against and rotating about sleeve 41.

The inner end of standard lever segment 33 is provided with a notch in each of its arms 37 by means of which it engages pin 53 set through stem 27, an arm 37 coming on either side of said stem.

When the operating lever, comprising interlocked segments 33 and 35, rocks in a counterclockwise direction, the inner end of segment 33 pushes up on washer or ring 31, which, through the intermediary of spring 32, raises diaphragm 20 for its compression stroke. Spring 32 has a predetermined amount of initial compression. When the operating lever rocks in a clockwise direction, the inner end of segment 33 solidly presses down on pin 53, effecting the suction stroke of the diaphragm. In Fig. 1, diaphragm 20 is at the upper limit of its stroke. This means that the pressure in fuel pump chamber 54 and outlet 55, which is connected to the carburetor by a fuel line, both the carburetor and the fuel line not being shown, is less than that required for spring 32 to yield, and that pin 53 is in contact with segment 33. Should the pressure in fuel pump chamber 54 in a subsequent compression stroke of diaphragm 20 be great enough to overcome the initial compression in spring 32, the inner end of segment 33 will rise without corresponding rising of stem 27, so that pin 53 will be located below the lower edge of said segment. In other words, there will be lost motion between segment 33 and stem 27. Under this condition, upon subsequent clockwise motion of the operating lever, which of course includes segment 33, there will not be any pull upon stem 27 at the beginning of the rotation of said segment, the latter catching on pin 53 only toward the end of the stroke. The reciprocation of diaphragm 20 by the operating lever through the intermediary of a spring, such as spring 32, is also described in my applications Serial Nos. 600,782, 633,333 and 644,535.

Fastened to the top of cover 22 at gasket 56, is glass strainer bowl 57 which is held in place by

the engagement of bail 58 with lugs 59 on the cover. Bail 58 presses bowl 57 down on gasket 56 through the intermediary of bolt 60, nut 61 and cap 62 as is well known in the art.

Cover 22 has two openings therein leading from fuel chamber 54. In one of said openings is set inlet check valve 63 and in the other is set outlet check valve 64. Cover 22 has a hollow cylindrical portion 65 extending up into bowl 20. At the bottom of portion 65 is inlet check valve 63 which allows the flow of fuel down from the inside of portion or tubular member 65 into fuel pump chamber 54 but not in the reverse direction. Cover 22 is provided with a fuel inlet which can be connected to the fuel tank, the inlet and tank not being shown. Fuel is delivered from the inlet to the space in the bowl outside of portion 65. An annular flange or baffle 66 is mounted on top of tubular member 65 so as to surround the latter. Screen 67 is mounted over the open upper end of portion 65. Baffle 66 acts to prevent any sludge which may have settled outside of portion 65 from reaching screen 67.

Screen 67 and flange 66 are held down on member 65 by spring 68, the upper end of which reacts against the inside top of bowl 57. The fuel flows through screen 67 into the inside of portion 65 and through check valve 63 into fuel pump chamber 54 when diaphragm 20 is moved downward, that is, has its suction stroke. Upon the upward or compression stroke of diaphragm 20, the fuel is forced through outlet check valve 64 into passage 69 and then through a second check valve 70, which happens to be in this particular embodiment a ball check valve. Ball 70 is held to its seat by spring 89 which is stiffer than the spring, not seen, in valve 64. The particular fuel filter just explained is also described in my application Serial No. 644,535 and the double outlet check valve in said application and in application Serial No. 619,710 of William Hicks and myself. From check valve 70, the fuel passes out of the pump through outlet 55 which is usually connected to the carburetor of an internal combustion engine. The use of the second check valve as shown has been found by experiment to act, instead of the usual air dome, as a pulsation dampener, that is the fuel flows from the pump to the carburetor in a substantially steady stream.

The pump and lever of Figs. 8, 9 and 10 illustrates the case where the same type of pump as is used in Figs. 1 and 2 can be used elsewhere to suit a different type of motor with a different relative position of its cam shaft 71. The only difference between the pump of Fig. 1 and the pump of Fig. 9 is in the removable lever segments 35 and 36. The construction and action of all the other parts is the same as that described before for Fig. 1. Segment 36 is formed with an angle between its portion having prongs 38 and 39 and its portion having bridge piece 72, the latter riding on cam 51, the pressure of spring 48 holding it there.

In Figs. 5, 6 and 7, both the standard lever segment 74 and the removable lever segment 75 differ from the corresponding segments shown in Figs. 1 and 9. The standard lever segment is formed of two arms 76 held together by rivet 81, the notched inner end of said arms straddling stem 27 and being adapted to engage pin 53. Arms 76 are pivotally mounted on sleeve 41. Removable segment 75 is formed of two arms 78 having between them a spacer block 85, all three parts being held together by rivets 79 and 80. The inner end of segment 75 is provided with a pair of upper prongs 83 and a pair of lower prongs

84 said prongs straddling sleeve 41 and providing segment 75 with a rotating fit thereon. Prongs 83 and 84 interlock with punched out bulge or projection 82 on arms 76. A lug 86 is provided on spacer block 85 for receiving the bottom of spring 48. Removable segment 75 is pinned to standard segment 74 by removable pin 87, the latter being kept in position by spring clip 88 under its head.

I claim:

1. A lever for use with driving means of an engine for operating a pump of standard design with a pivot for the mounting of the lever, said lever comprising two segments, the first of said segments being standard and mounted on the pivot for rockably mounting said first segment on the pump, the second of said segments overlapping the first and having readily separable interlocking engagement with it at a plurality of locations other than at the pivot, the second segment being provided with a notch, engaging and containing the pivot in the notch, one of the legs formed by the notch passing on one side of the pivot and the other of said legs passing on the other side of the pivot, said second segment being rockable in both directions together with the first segment in fixed relation therewith and being adapted to engage the driving means of the engine.

2. A lever for use with driving means of an engine for operating a pump of standard design with a pivot for the mounting of the lever, said lever comprising two segments, the first of said segments being standard and mounted on the pivot, the second of said segments being notched and set on the pivot at the notch, the open end of the notch being toward the inside of the pump, a lateral projection on the first segment located toward the inside of the pump from the pivot, the second segment having a portion extending into the pump beyond the pivot into removable engagement with said projection, and readily removable means for fastening both segments together on the side of the pivot away from the pump, said second segment being of such form on the latter side to engage said driving means.

3. A lever for use with driving means of an engine for operating a pump of standard design with a pivot for the mounting of the lever, said lever comprising two segments, the first of said segments being standard and being made of two plate-like arms, the flat of one arm being substantially parallel to the flat of the other, means for holding the arms in spaced relation, the pivot passing through aligned holes provided in said arms for pivotally mounting them on the pump, the second of the segments also being formed of two substantially parallel plate-like arms, means at their end outside of the pump for holding the latter arms together in such spaced relation to come alongside of the arms of the first segment, the arms of the second segment being notched and set on the pivot at the notch, the open end of the notch being toward the inside of the pump, a lateral projection on each arm of the first segment located toward the inside of the pump from the pivot, the arms of the second segment extending into the pump beyond the pivot into removable engagement with said projections, and a readily removable pin set through aligned openings in the four arms on the side of the pivot outside of the pump, said second segment being of such form on the latter side to engage the driving means.

4. A lever for use with driving means of an

engine for operating a pump of standard design with a pivot for the mounting of the lever, said lever comprising two segments, the first of said segments being standard and having the pivot 5 pass through a hole in it for pivotally mounting said first segment on the pump, the second of said segments being notched to form upper and lower prongs, said second segment being set on the pivot at the notch, the open end of the notch 10 being toward the inside of the pump, a lateral projection on the first segment located toward the inside of the pump from the pivot, said upper prong being in readily removable engagement with said projection, and readily removable means for fastening both segments together on the side of the pivot away from the pump, said second segment being of such form on the latter side to engage said driving means.

5. A lever for use with driving means of an engine for operating a pump of standard design with a pivot for the mounting of the lever, said lever comprising two segments, the first of said segments being standard and having the pivot 20 pass through a hole in it for pivotally mounting said first segment on the pump, the second of said segments being notched to form upper and lower prongs, said second segment being set on the pivot at the notch, the open end of the notch 25 being toward the inside of the pump, a lateral projection on the first segment located toward the inside of the pump from the pivot, said upper prong being in readily removable engagement with said projection, and readily removable means for fastening both segments together on the side of the pivot away from the pump, said second segment being of such form on the latter side to engage said driving means.

6. A lever for use with driving means of an engine for operating a pump of standard design 40 with a pivot for the mounting of the lever, said lever comprising two segments, the first of the segments being standard and having the pivot pass through a hole provided in it for pivotally mounting the first segment on the pump, the 45 second of said segments overlapping the first and having a readily separable engagement with it at a location toward the inside of the pump from the pivot, a readily removable pin set through openings provided in both segments on the side 50 of the pivot away from the pump, said second segment being of such form on the latter side to engage said driving means, a clip hooked over the pivot at one end and having its other end 55 rest against said pin, and a spring extending between said latter end of the clip and the pump, pressing the clip against the pin.

7. A lever for use with driving means of an engine for operating a pump of standard design 60 with a pivot for the mounting of the lever, said lever comprising two segments, the first of the segments being standard and mounted on the pivot, the second of said segments having a readily separable engagement with the first segment 65 at a location toward the inside of the pump and at a location on the side of the pivot away from the pump, said second segment being of such form on the latter side to engage said driving means, a clip engaging the pivot at one end and 70 engaging the first segment at its other end at a location on the side of the pivot away from the pump, and a spring extending between said latter end of the clip and the pump, pressing the clip to swing the lever as a whole.

8. A lever for use with driving means of an

engine for operating a pump of standard design with a pivot for the mounting of the lever, said lever comprising two segments, the first of said segments being standard and being made of two plate-like arms fastened flat against each other, said arms being mounted on the pivot, the second of the segments also being formed of two plate-like arms fastened together in spaced relation to overlap and embrace the arms of the first segment, a lateral projection on each arm of the first segment located toward the inside of the pump from the pivot, the arms of the second segment extending into the pump beyond the pivot into removable engagement with said projections, and readily removable means for fastening both segments together on the side of the pivot outside of the pump, said second segment being of such form on the latter side to engage the driving means.

9. A lever for use with driving means of differently constructed engines for operating pumps of the same design, a spring provided on the pump, the driving means rocking the lever in one direction against the resistance of the spring, said spring rocking the lever in the opposite direction, said lever comprising two segments, the first of said segments being the same for all pumps of said design and pivotally mounted thereon, and the second of said segments being readily removably attached to the first of said segments in rigid connection thereto to rock in both directions in fixed position thereon, the second of said segments being of a form to reach and engage the driving means of the particular engine used to drive the pump, and means pro-

5 vided on one of said segments for engagement with the spring.

10. A lever as claimed in claim 9 in which the means for engaging the spring is located on the first segment.

11. A lever for use with driving means of differently constructed engines for operating pumps of the same design mounted on said engines, a spring provided on the pump, the driving means rocking the lever in one direction against the resistance of the spring, said spring rocking the lever in the opposite direction, said lever comprising two segments, the first of said segments being the same for all pumps of said design and pivotally mounted thereon, the second of said segments being of a form to reach and engage at one end the driving means of the particular engine on which the pump is mounted, and to have its other end readily removably attached to the first segment in one fixed position and rigid thereon for all positions of the segments during their reciprocation, and means provided on one of said segments for engagement with the spring.
